UNITED STATES PATENT OFFICE

2,523,727

LATCH

Harry D. Severson, Elkhart, Ind., assignor to The Adlake Company, Chicago, Ill., a corporation of Illinois

Application October 5, 1945, Serial No. 620,469

2 Claims. (Cl. 292—128)

1

My invention is concerned with an improved latch construction which is particularly adapted for use on a horizontal sliding window sash.

It is an object of my invention to provide a latch construction, adapted to be mounted on a horizontal sliding window sash, of the type now installed in modern automobile busses or the like, having means for engagement with a keeper member on the frame, which will positively and securely retain the sash in closed position, but, which is readily releasable by a force exerted in the direction of opening movement of the sash.

It is a further object of my invention to provide a latch mechanism of the type described which is simple in construction and which may be readily manufactured from continuously extruded metal shapes or similar material.

Other objects and advantages will be apparent from a description of the preferred form of my construction which is shown by way of example in the accompanying drawings wherein:

Fig. 1 is an elevation of a horizontal sliding window sash equipped with my latch mechanism;

Fig. 2 is a section on an enlarged scale taken on the line 2—2 of Fig. 1;

Fig. 3 is a perspective view of an extruded metal shape, a section of which may be used to form the fixed or base member of my latch;

Fig. 4 is a perspective view of an extruded metal shape, a section of which may be used to form the movable member of my latch;

Fig. 5 is an enlarged view of my latch and the cooperating keeper member installed on a window sash and frame, respectively, with the members in disengaged position;

Fig. 6 is a view taken on the line 6—6 of Fig. 5 showing the latch mechanism mounted on the sash;

Fig. 7 is a section taken on the line 7—7 of Fig. 6; and

Fig. 8 is a section taken on the line 8—8 of Fig. 6.

The preferred embodiment of my invention is illustrated in the drawings as installed on a horizontal sliding sash 10 which is mounted in a frame 11 secured in a window aperture in a vehicle wall 12. The sash 10 is slidably mounted in the frame 11 and cooperates with a fixed sash 13, which is also mounted in the frame, to provide a complete closure for the window when the sliding sash 10 is in the position shown in Fig. 1.

My latch mechanism 14 (Figs. 1, 2 and 5) is attached to the sliding sash 10 and includes a movable catch member 15 which cooperates with a conventional keeper plate 16, attached to the

2

frame 11, to securely retain the sash 10 when it is in closed position and the catch 15 is engaged with the keeper plate 16.

Reference will be made to the method of manufacturing the parts of my latch in order to more clearly illustrate its construction and the advantages thereof. As illustrated in Figs. 3 and 4 the two main members of the latch are each produced by forming a continuously extruded shape of the cross section required for the member. These shapes are produced by well known methods of extruding metal or similar material. The shapes 17 and 18 are produced continuously in the form of a channel or bar and then cut into sections of predetermined length to provide a supply of latch members 19 and 20, respectively (Fig. 7).

The latch member 19, which is a predetermined length of the generally channel-shaped extrusion 17, is provided with a base flange 21, a side wall 22 and a top flange 23. The base flange 21 is adapted to be secured to the frame 24 of the sash 10 by means of screws 25, or the like. The side wall 22 extends in a generally lateral or very nearly perpendicular direction from the base flange 21 at the inner edge thereof. A tubular shaped bore or recess 26 is provided, at the intersection of the base flange 21 and the side wall 22, with an opening 27 directed inwardly in the general direction of the top flange 23. The outer edge of the top flange 23 is provided with an inwardly directed abutment surface 28 and a recess 29 is provided on the inner side of the side wall 22 intermediate the base and top flanges.

The latch member 20 which is a predetermined length of the generally T-shaped extrusion 18 is somewhat shorter than the latch member 19 and is provided with a rounded or beaded portion 30 along one edge of the top or base 31 thereof. The rounded edge is constructed to be received in the bore 26 of the latch member 19 to form a hinged connection therewith. The opposite top edge of member 20 is provided with an abutment surface 32 adapted to engage with the abutment surface 28 on the latch member 19 to limit the outward movement of the member 20 about the hinge connection with member 19. A laterally extending bead 33 is provided on the inside top edge of the member 20 in laterally spaced relation to the abutment surface 32 to provide a protuberance upon which pressure may be applied by the operator to pivot member 20 about its hinged connection with member 19. Movement of the member 20 to the unlatched position which is indicated by dotted lines in Fig. 7 is opposed by a leaf or wire spring 34 re-

ceived in the recess 29 of member 19 and a similar recess 35 in the member 20. The stem 36 of the T-shaped section 20 is cut away at the ends thereof as indicated at 37 to provide the laterally extending catch member 15 having the inwardly directed projection 38 thereon for engagement in the aperture 39 of the keeper plate 16.

The latch members 19 and 20 are restrained from longitudinal movement relative to each other by small plugs 40 provided with circumferential grooves 41 which are clinched at 43 in the ends of the bore 26.

My latch structure is particularly designed to be applied to the horizontal sliding sash type of window. When it is desired to open the window by sliding the sash 10 to the right as shown in Fig. 1, the operator grasps the members 19 and 20, between the thumb and forefinger, respectively, and by pressure of this thumb on the protuberance 33 of member 20, first disengages catch member 15 from the keeper plate 16, and then, by continued pressure, moves the sash 10 to open position. When sash 10 is moved to the left in Fig. 1 to close the window, the rounded surface 42 of the catch member 15 will strike the forward edge of the keeper plate 16 and the catch 15 will ride up over the forward portion of the keeper plate 16 and allow the projection 38 to snap into the aperture 39 of the keeper plate. By this arrangement the latch 14 performs the dual function of a latch and a handle member for moving the sash.

While it is preferred to manufacture the two main members 19 and 20 of the latch from the continuous metal extrusions 17 and 18, as described, it will be understood that these members may be made of other materials and in any other desired manner, such as casting, or the like.

I claim:

1. A latch mechanism for a sliding sash window, or the like, comprising an elongated channel-shaped outer member adapted to be fixedly secured to the window sash by one flange, a hinge groove on the inside of said flange, an inwardly directed projecting abutment member on the outer edge of the other flange, an elongated inner generally T-shaped member having one edge of the top thereof cooperating with said groove to form a hinge connection between said inner member and said outer member and having the other edge of the top projecting behind said inwardly projecting abutment, a spring member between the inner and outer members urging the edge of the top of the inner member into engagement with the said inwardly projecting abut-

ment, the stem of the inner member projecting outwardly from the top thereof and cut away at both ends thereof, a laterally projecting keeper engaging projection on said stem, the inner member being somewhat smaller in length than the outer member, and means to prevent the inner latch member from moving longitudinally of the outer member.

2. A latch consisting of a length of extruded material having a generally channel-shaped cross section, said length of material constituting a fixed member for said latch and adapted to be secured to one of two relatively movable members, said channel-shaped member having a tubular hinge groove along the inner side of one leg thereof and an inwardly directed abutment flange along the inner side of the other leg in spaced relation to the base of the same, a shorter length of extruded material having a generally T-shaped cross section, said length of material constituting a movable member for said latch, said T-shaped member having a cylindrical shaped bead along one edge thereof mounted for hinged movement in the tubular hinge groove in said channel-shaped member, the oppositely disposed edge of said T-shaped member being positioned between the base of said channel-shaped member and said inwardly directed flange on said other leg thereof, the third edge of said T-shaped member extending outwardly from the channel-shaped member and having a laterally extending portion adapted to engage with a latch keeper member secured on the other one of said relatively movable members, a spring member arranged to urge said T-shaped member outwardly from said channel-shaped member and thereby urge the laterally extending keeper engaging member toward the hinge carrying leg of said channel-shaped member, and means restraining said members against longitudinal movement.
